Patented Nov. 29, 1921.

UNITED STATES PATENT OFFICE.

WILLIAM A. BRADEN, OF CLEVELAND, OHIO, ASSIGNOR OF ONE-HALF TO THEODORE H. EICKHOFF, OF CLEVELAND, OHIO.

TRACK CONSTRUCTION.

1,398,932.

Specification of Letters Patent. Patented Nov. 29, 1921.

Application filed June 28, 1919. Serial No. 307,395.

To all whom it may concern:

Be it known that I, WILLIAM A. BRADEN, a citizen of the United States of America, and resident of Cleveland, in the county of 5 Cuyahoga and State of Ohio, have invented new and useful Improvements in Track Construction, of which the following is a specification.

This invention relates to track construction and more particularly to an improvement 10 in the type of track construction disclosed in Patent No. 893,134, granted to me July 14, 1908, and in Patent No. 927,216, granted to me July 6, 1909.

Heretofore, as far as I am aware, the running rails have been spiked or otherwise secured to cross-ties which support them upon the roadbed. With this construction, when a heavy rolling load passes over the rails, the 15 cross-ties are depressed into the ballast of the roadbed during the period of application of the load and, in view of the fact that the ties are fastened to the rails, they follow the rebound of the rails after the passage of the 20 load and are lifted from a bearing contact with the ballast. There are therefore many ties which do not support the rails, but merely rise and fall with the track wave unless the load is sufficient to depress them low 25 enough to reach a bearing upon the ballast. Inasmuch as the lower supporting surfaces of the cross-ties are customarily buried in the ballast, it is almost impossible to determine the extent to which the ties bear upon the 30 ballast under conditions of no load or comparatively light load.

An object of my invention is to provide a substantially continuous support for the rails of a track interposed between the rails 40 and the ballast. A further object of the invention is to provide means for supporting rails upon the roadbed and retaining them at the proper gage without the use of supporting ties attached to the track. These 45 objects are attained by supporting the rails upon plates or the like disposed between the rails and the roadbed and unattached to the rails but in intimate contact with both the rails and the roadbed when the rails are 50 without load, and by holding the rails in alignment and at the proper gage by gage bars.

A further object of my invention is to

provide simple means for securing the rails to the gage bars which also replace the usual 55 fish-plates at the rail joints allowing expansion and contraction at both ends of each rail.

A still further object of my invention is to provide a track construction which is simple and durable and less expensive to maintain than track construction heretofore proposed. This object is attained by providing a construction which eliminates the ties, tie- 60 plates, spikes, anchoring devices, fish-plates, 65 and bolts necessary in the track construction now widely in use.

Other objects of the invention will appear from the following description and accompanying drawings in which I have disclosed 70 certain illustrative species of the genus of my invention.

Figure 1 is an elevational view showing one embodiment of my invention in which the rails are supported upon concrete plates 75 or blocks;

Fig. 2 is a section taken on line 2—2 of Fig. 1;

Fig. 3 is an elevational view showing the manner of supporting rail joints in accordance with the embodiment disclosed in 80 Fig. 1;

Fig. 4 is a section taken on line 4—4 of Fig. 1, showing the rail insulated from the 85 securing means;

Fig. 5 is a plan view of a portion of the track shown in Fig. 1 showing the concrete omitted in the region of the gage bars;

Fig. 6 is a longitudinal section taken on line 6—6 of Fig. 4;

Fig. 7 is an elevational view showing a further embodiment of my invention in which the rails are supported upon metal plates and modified gage rods are employed;

Fig. 8 is an elevational view showing the 95 manner of supporting rail joints in accordance with the embodiment of Fig. 7;

Fig. 9 is a section taken on line 9—9 of Fig. 7;

Fig. 10 is a section taken on line 10—10 100 of Fig. 7;

Fig. 11 is a top plan view of the central portion of track construction shown in Fig. 7 with the supporting plate omitted;

Fig. 12 is a longitudinal section through 105 the rail securing means shown in Fig. 11.

taken on a line substantially through the flange of the stiffening member;

5 Fig. 13 is a plan view of a section of track constructed in accordance with the embodiment of Fig. 7;

Fig. 14 is a side view of the section of track shown in Fig. 13;

10 Fig. 15 is a detail of gage bars which may be employed on curves;

Fig. 16 is an end view of the construction shown in Fig. 15; and

Fig. 17 is a detail of a modified form of gage bar which may be employed on tracks which employ only running rails.

15 Referring to Figs. 1 to 6 inclusive, I have shown a portion of track constructed in accordance with one embodiment of my invention in which the running rails are shown at 1. Beneath the rails and parallel thereto 20 are reinforcing or stiffening members 2 which are preferably in the form of bulb or deck beams as shown. For maintaining the gage between the running rails, gage bars 3 are provided. The rails 1 are held in fixed 25 relation to the members 2 and to the gage bars by means of securing means 4 comprising clamping members 5 and 6 substantially channel-shaped in cross-section and opposed to each other on opposite sides of the rails 30 and stiffening members. These clamping members are shaped to fit the flanges of the members 1 and 2, and are spaced along the track at intervals as shown in Fig. 1. Each clamping member is provided with a trans- 35 verse opening through which the end of a gage bar 3 passes, and with a lug 12 as shown in Fig. 6 for engagement with a notch in the flange of the rail to prevent the clamps from moving along the rail.

40 The gage bar is formed with a thickened end 7 slotted as at 8. Positioned within the slot on either side of rail 1 for coöperation with clamping members 5 and 6 is a gib 9 and key 10. With the construction 45 above described the position of the rails 1 relative to gage bars 3 may be adjusted to determine the gage of the track and the rails and stiffening members 2 are clamped rigidly together.

50 Interposed between the base of the rails 1 and the ballast of the roadbed are plates or blocks of concrete 11. These track plates extend substantially from one securing means 4 to the next, but do not inclose them. Each 55 rail is thus independently supported by a substantially continuous series of concrete plates which rest upon the ballast but are unattached to the rails. In Fig. 2 the concrete is shown as extending up underneath the ball of the rail on the outside of the rail and down upon both sides of the stiffening member 2.

If desired, when the rails are employed as conductors for operating train signals, the 60 rails 1 may be insulated from the clamping

means 4 by suitable insulation 13 as shown in Figs. 4 and 6.

At the joints between abutting rails a securing means 14 is employed which is preferably wider than the securing means 4. 70 The means 14 comprises two opposed clamping members and is arranged to receive the ends of two gage bars 3 in the same manner as described hereinbefore in connection with securing means 4. By providing a securing means of considerable length at the rail joints, the usual fish plates, bolts and bolt holes in the ends of the rails for holding abutting rails in alinement are made unnecessary.

80 From the foregoing description it is evident that with my improved track construction, each running rail is separately supported upon the roadbed by a substantially continuous series of concrete blocks. These 85 blocks are unattached to the rails and therefore the rails are free to move vertically relative thereto. In the normal or quiescent condition of the track the blocks are tamped until they bear firmly underneath the flange 90 of the rails. Upon the application of a rolling load to the rails the blocks then transmit the load directly to the roadbed. After removal of the load the blocks not being attached to the rails do not rebound with the 95 rails but retain their depressed position on the roadbed. If then any blocks are insufficiently tamped a space will be left between the rail and blocks which is readily apparent to the track inspector. Such 100 blocks may then be properly tamped until the rails are firmly supported by all of the blocks. The stiffening members 2 assist the rails to distribute the load over a large 105 number of blocks, reducing to a minimum the contortion of the rails by improving the moment of inertia.

110 In Figs. 7 to 12 I have disclosed a modified form of my invention in which metal track plates are employed in the place of concrete plates and in which a modified form of gage bar is used. The running rails are shown at 1 connected to the stiffening members 2 by securing means 15 and 25. Each securing means 15 comprises apertured 115 clamping members 16 and 17, channel-shaped in cross-section. Passing through the apertures in the clamping members are gage bars 18 substantially I-shaped in cross-section. The ends of each bar 18 where they pass through the members 16 and 17 are provided as shown in Fig. 9 with keyways 19 and 20 formed by removing portions of the web of the bar and slotting the flanges of the bar above and below the openings in 120 the web. The metal which is struck out to form the slots in the flanges of the bar for keyway 19 is not entirely removed but bent into the opening in the flange as at 21 and 22 to form a gib. A key 23 is positioned in 125

keyway 20 for coöperation with the clamping member 17 and a key 24 is positioned in keyway 19 for coöperation with member 16. By adjustment of the keys in their respective keyways the clamping members are caused to grip the flanges of the rails and stiffening members, and the position of the rail relative to the gage bar 18 is determined for the purpose of fixing the gage of the track.

In Figs. 7, 11 and 12, I have shown a means for securing the rails to the stiffening members at the joints where two stiffening members abut. These securing means 15 are similar to the securing means 15 except that they are wider to more fully embrace the ends of both members 2 and are provided at 26 as shown in Fig. 12 with lugs which enter between the ends of the members 2 for the purpose of preventing the means 25 from sliding along the rail.

In Fig. 8 I have shown a form of securing means for securing the rails to the stiffening members at the joints of the rails. This securing means 27 is made wide enough to embrace a substantial portion of the abutting ends of rails 1 and is provided with apertures through which two gage-bars 18 pass and are secured by wedges 23 and 24 in the manner shown in Fig. 9.

For transferring the load from the running rails 1 to the roadbed, plates 28 are provided. These plates may be rolled from steel plate or cast from steel or iron as desired, and are adapted to engage beneath the flange of the rails when the ballast of the roadbed has been well tamped beneath them. As shown in Fig. 7, the plate 28 extends between securing means 15 beneath and parallel to the rail 1 and is provided with an opening 29 through which the clamping members of securing means 25 extend.

In Figs. 13 and 14 I have disclosed a complete section of track employing track plates 28 for supporting the rails in the region of the joints between stiffening members and shorter plates 30 between adjacent securing means 15.

At curves, Y's, switches, etc., the rails 1 and stiffening members 2 may be secured together by clamps 31 of substantially L-shaped cross-section as shown in Figs. 15 and 16. The rail 1 rests upon the upper flange of the clamp which is cast or otherwise formed with a lip 32 which overlies one edge of the base of the rail. The clamp rests by its lower flange upon the upper surface of the flange of member 2, the flange of the clamp being formed along its outer edge with a lip 33 which embraces the outer edge of the flange of member 2. For clamping the inner edges of the rail base and flange of member 2 to the flanges of clamp 31 the gage bars 34 and 35 are secured by bolts 36 to the flanges of clamp 31 with their ends over-

lying the base of the rail and flange of member 2 as clearly shown in Fig. 15. To secure a more efficient bracing of the rails for preventing any tendency for them to turn about their longitudinal axis the gage bars 34 and 35 are crossed as at 38, each bar extending from the upper flange of member 31 on one side of the track to the lower flange of member 31 at the other side of the track.

The concrete or metal track plates hereinbefore described may be used with the ordinary tracks being placed beneath the rails where ties become rotted out, or every other cross-tie may be removed and plates inserted. The remaining cross-ties then serve principally as gage maintaining means. The track plates may also be used as a supporting medium throughout the entire track, the cross-ties then being entirely eliminated and the rails held to gage by gage bars which might be of the general form shown in Fig. 17. These gage bars comprise two members 39 and 40, secured together by suitable means as bolts 41.

By supporting the running rails upon track plates, the track is more firmly supported than by the track construction heretofore proposed resulting in relatively less track wave, in grade reduction and consequently in a greater efficiency in the motive power both on level running and hill climbing. The rolling stock is subjected to less vibration and in consequence the cost of maintenance of the rolling stock is materially reduced.

The track plates, inasmuch as they overlie the stiffening members will to a large extent prevent rain or snow-water from accumulating adjacent to or in sub-soil of the ballast surrounding the stiffening members and will thereby prevent the formation in winter weather of hard frozen spots beneath the rails which would seriously affect the smoothness of operation over the track. The plates also having extensive surfaces will reduce the expansion and contraction of the rails by absorbing heat from the rails in summer and giving off heat to them in the winter. The rails may therefore be laid with their ends in relatively close association.

By providing the track plates unattached to the running rails, their supporting contact with the rails can be readily ascertained by the track walker or inspector, and if found out of contact with the under side of the rails when the track is without load, the condition of such plates can be reported for proper tamping.

While I have shown one form of gage bar associated with a specified type of track plate, it will be understood that the different types of track plates which I have illustrated, by way of exemplification, may be used interchangeably with any of the forms of gage bars herein illustrated.

I claim:

1. In railroad track construction, the combination of rails, means connecting with the rails and extending downwardly into the roadbed for restraining lateral movement of the rails, and means underlying said rails in extensive contact with the roadbed for supporting said rails, said last means being unattached to the rails or other supporting elements. 10
2. In railroad track construction, the combination of rails, vertically disposed members extending from the rails into the roadbed for restraining lateral movement of the rails, horizontally disposed members interposed between said rails and the roadbed for supporting the rails, said first members being attached to the rails and said second members being unattached to the rails and to 20 said first members. 15
3. In railroad track construction, the combination of rails, parallel flanged stiffening members therebeneath, means for maintaining the gage of the track, and supporting means disposed beneath each rail and between adjacent gage means, said supporting means having detachable contact with the underside of said rails for supporting the rails upon the roadbed. 25
4. In railroad track construction, the combination of rails, parallel flanged stiffening members therebeneath, means for clamping the rails and the stiffening members together, means for maintaining the gage of the track adjustably connected with said clamping means, and plates disposed beneath each rail for supporting the rails upon the roadbed. 30
5. In railroad track construction, the combination of rails, parallel flanged stiffening members therebeneath, securing means comprising pairs of opposing clamps adapted to engage flanges of the rails and the stiffening members and gage bars for maintaining the gage of the track and having adjustable connection with said securing means, whereby the gage of the track may be adjusted, and the said clamps secured against the rails and stiffening members. 45
6. In railroad track construction, the combination of a rail, securing means comprising a pair of opposing clamps each adapted to engage the flange of the rail, a slotted gage bar passing through said clamps beneath the flange of the rail, and gibs and keys within said slot for forcing said clamps against the rail. 50
7. In railroad track construction, the combination of a rail, a flanged stiffening member beneath and paralleling the rail, means for securing the rail to the member comprising a pair of opposing apertured clamps each adapted to engage flanges of the rail and stiffening member, a slotted gage bar passing through said clamps between the rail and said member, and gibs and keys within the slot for forcing said clamps against the rail and member. 55
8. In railroad track construction, the combination of a rail, a flanged stiffening member beneath and paralleling the rail, means for securing the rail to the member comprising a pair of opposing apertured clamps, each adapted to engage flanges of the rail and the stiffening member, a slotted gage bar passing through said clamps between said rail and said member, and a gib and key within the slot and in association with each clamp for forcing the clamps against the rail and member. 60
9. In railroad track construction, the combination of a rail, a flanged stiffening member beneath and paralleling the rail, means for securing the rail to the member comprising a pair of opposing apertured clamps, each clamp being channel-shaped in cross-section and adapted to engage flanges of the rail and the stiffening member, a slotted gage bar passing through said clamps, and gibs and keys within the slot and embraced by the flanges of said channel-shaped clamps for forcing said clamps against the rail and member. 65
10. In railroad track construction, the combination of abutting rails, a flanged stiffening member beneath and paralleling the rails, means for securing the ends of said rails together and to the member comprising a pair of opposing apertured clamps, each being adapted to engage flanges of the rails and the stiffening member, a slotted gage bar passing through said clamps, and a gib and key within the slot and in association with the clamps for forcing them into association with the rails and member. 70
11. In railroad track construction, the combination of abutting rails, a flanged stiffening member beneath and paralleling the rails, means for securing the ends of said rails together and to the member comprising a pair of opposing apertured clamps, each being adapted to engage flanges of the rails and the stiffening member, slotted gage bars passing through said clamps, and gibs and keys within the slots and in association with each clamp for forcing the clamps against the rail and member and adjusting the gage of the track. 75
12. In railroad track construction, the combination of a rail, a flanged stiffening member beneath and paralleling the rail, means for securing the rail to the member comprising a pair of opposing apertured clamps, each clamp being adapted to engage flanges of the rail and the stiffening member, a gage bar of substantially I-shaped cross-section passing through said clamps, the web of said bar being cut away near its end and its flanges slotted to form a keyway, and a key within the keyway and in 80

association with each clamp for forcing the clamps against the rail and member.

13. In railroad track construction, the combination of a rail, a flanged stiffening member beneath and paralleling the rail, means for securing the rail to the member comprising a pair of opposing apertured clamps, each clamp being adapted to engage flanges of the rail and the stiffening member, 5 a gage bar of substantially I-shaped cross-section passing through said clamps, said bar being provided with keyways formed by removing a portion of the web of the bar and striking in portions of the flanges of the bar 10 into the opening so formed in the web, and a key within each keyway and in association with each clamp for forcing the clamps against the rail and member.
14. In railroad track construction, the combination of rails, flanged stiffening members beneath and paralleling the rails, means for securing the rails to the members, and gage bars for maintaining the gage of the track and for clamping said rails and 15 members to said securing means.
15. In railroad track construction, the combination of rails, flanged stiffening mem-

bers beneath and paralleling the rails, means for securing the rails to the members, gage bars for maintaining the gage of the track 30 and for clamping said rails and members to said securing means, and plates disposed beneath and paralleling the rails for supporting the rails upon the roadbed.

16. In railroad track construction, the combination of rails, flanged stiffening members beneath and paralleling the rails, means for securing the rails to the members, gage bars for maintaining the gage of the track 35 and for clamping said rails and members to 40 said securing means, and means for insulating said rails from said securing means.

17. In railroad track construction, the combination of rails having notched flanges, flanged stiffening members beneath and paralleling the rails, and means for securing the rails to the members, said means being provided with lugs for engagement in the notches of the flanges of the rails to prevent 45 longitudinal movement of said means along 50 said rails.

Signed by me at Cleveland, Ohio, this twenty-fourth day of June, 1919.

WM. A. BRADEN.
